(57) **CLAIM**

The ornamental design for a perfusion module lid, as shown and described.

DESCRIPTION

FIG. 1 is a top plan view of a perfusion module lid showing our new design.

FIG. 2 is a bottom plan view, thereof.

FIG. 3 is a left side elevational view, thereof.

FIG. 4 is a right side elevational view, thereof.

FIG. 5 is a front side elevational view, thereof.

FIG. 6 is a rear side elevational view, thereof; and,

FIG. 7 is a top, right and rear perspective view, thereof.

The lid comprises five port openings with four (4) arranged in an arc ranging across the midsection and a fifth port located on the rear edge.
